[57] **ABSTRACT**

A mechanical memory of the code pin switch activating type employs a plurality of compression loaded code pin members arranged in a containing means which permits lateral translation of each of the pins in a row orientation while constraining the pins from translation transverse the pin row. The pins are substantially square headed and are formed with a head slot which may be selectively oriented so as to be coextensive with or transverse of the pin row axis. Cooperating switch activating members are loaded against the pinheads such that selected pin slot orientations define respective first and second positions of the actuator member.

**CAM-OPERATED ELECTRIC TIMING MECHANISM
WITH IMPROVED ADJUSTABLE PIN CODING AND
RETAINING STRUCTURE**

This invention relates generally to mechanical memory systems and more particularly to an electromechanical arrangement positioning a plurality of switches in one or the other of two positions so as to effect a preselected permutation of relative switch positions.

The invention is generally embodied in the provision of a plurality of adjustable mechanical devices (herein referenced to as code pins) arranged to coact with a plurality of switch actuating members to position a switch associated with each actuator to one of two predetermined positions, and by means of which mechanical adjustment to effect preselected switch position permutations of a bank of switches may be readily effected.

Mechanical memory systems of a type employing rows of pin members carried on a drum are known in the art wherein the relative positions of the pin members defining a given row of pins effects predetermined position permutations of actuating members actuated from a first to a second position upon mechanical engagement with a pin member. Devices of this general type inherently define a storage problem as concerns the pin members in a bank. For example, a bank of pin members in certain systems are positioned to one of two lateral positions along a pin row so as to selectively engage or not engage a cooperating switch activating arm. Obviously in such systems a lateral dimension, that is, the length required for a given row of pins, is at least double the lateral dimension defined by the pin members per se, since each pin must be positionable to two discrete lateral positions.

Other mechanical memory systems employing selectively positioned pin members for cooperative engagement with associated switching devices may solve the lateral storage space requirement by means which cause the pin to either project from the surface of a drum member carrying the pin row or, by a radial inward positioning means, be recessed so as to not engage the cooperating one of a bank of switch-actuating members.

The present invention has as a primary object thereof the provision of a mechanical memory system wherein lateral storage requirements are essentially obviated as well as radial storage requirements, by an assembly providing decided advantages of low cost and reliability due to the simplicity of the arrangement and the minimal number of parts required for implementation.

A further object of the invention is the provision of a switch positioning code pin assembly with positive detenting for both binary positions of the individual pins.

The present invention is featured in the provision of a code pin or actuating pin assembly comprised of a plurality of compression-loaded code pin members arranged in containing means permitting lateral translation of each of the code pins in a pin row and permitting rotation of each of the pin members while constraining the pin members from translation transverse to the axis of the pin row. Each of the pin members carries a transverse slot on the face thereof which may be selectively oriented so as to be coextensive with or transverse of the pin row axis. A plurality of cooperating switches are each provided with a switch actuating member spring loaded into a camlike relationship with the associated one of the pin members whereby the pin slot orientation defines respective first and second positions of the actuating member addressing each code pin face.

These and other features and objects of the present invention will become apparent upon reading the following description with reference to the accompanying drawings in which:

FIGS. 1, 2, and 3 are respective top, side, and the bottom views of a code pin member utilized in the present invention.

FIG. 4 illustrates a plurality of code pin members arranged in a confined and spring-loaded code pin row assembly in accordance with the present invention;

FIG. 5 illustrates a cooperating switch-actuating member in engagement with a code pin; and

FIGS. 6 and 7 illustrate an embodiment of a plurality of rows of code pin assemblies arranged in a drumlike configuration rotation of which effects a preselected position permutation of a plurality of switches as defined by the pin face slot orientation in a selected code pin row.

As above described, the present invention provides for a bank or row of code pin members the mechanical positioning permutations of which effect predetermined electrical switch connections of an associated bank of switch members. Each switch member includes an actuating or contact arm in spring loaded mechanical engagement with an individual one of the pins in the row. As will be described, a preselected permutation of code pin orientations in a row effects a relative position permutation of an associated bank of switches. By embodying a plurality of rows of pin members each adjusted to one of two position orientations, an associated bank of switches may be selectively actuated to define a predetermined permutation of switch positions in accordance with the "mechanical memory" set in a selected pin row which is caused to engage the plurality of switches.

The basic code pin member of the present invention is illustrated in FIGS. 1, 2, and 3. The code pin 10 is formed with a substantially square face member 11 the corners 13 of which may be formed with a predetermined radius. As illustrated in FIG. 1, the face 11 has formed therein a transverse slot 12. The portion of the pin opposite the face member 11, as best shown in FIGS. 2 and 3, is formed with a radial groove 8 such that the pin member is terminated in an annular ring portion 14.

A basic pin row assembly in accordance with the present invention is illustrated in FIG. 4. Four pin members 10a-10d are shown in stacked position and retained by means of guide rail members 15 and 16 which are arranged in parallel-spaced relationship between fixed mounting members 18 and 19. The radial groove 8 formed in each of the pin members 10a-10d captivates the pin members within the guide rail assembly but permits rotation of each of the pin members 10a-10d within the plane of the guide rails. The length of the guide rails 15 and 16 is in excess of that defined by the lateral dimensions of the faces 13 of each of the pin members, and a spring loading means comprising a loading member 9 and compression spring 17 urges the pin members 10a-10d into spring-loaded juxtaposed relationship.

Loading member 9, unlike the pin members 10a-10d, is formed with opposed slots into which guide rails 16 and 17 are received, and thus member 9 may translate along the pin row axis but is constrained from rotation. The spring loading means establishes a relative position detent as concerns the squareheaded pin members 10a-10d. When any one of the pin members 10a-10d is rotated in 90° detented steps, the detent action is accomplished as the longitudinal dimension of the pin being rotated changes through the rotation action causing the spring 17 to first be further compressed and then released to realign the square pin heads to the stacked position illustrated in FIG. 4. The corners of each of the heads of the pin members 10a-10d may be formed with a slight radius and the pins themselves comprised of an insulating molding material of desired lubricity to permit rotation of any one of the pin members to change the position permutation of the pin row without transmitting rotation to other pins in the row.

FIG. 5 illustrates the manner in which the relative orientation of the face slot in any one pin member 10 in the assembly of FIG. 4 effects binary positioning of a cooperating switch means. Pin member 10c is depicted in the cross section view of FIG. 5 with its face slot 12 aligned in vertical position. A cooperating switch contact arm 20, which may be constructed of a resilient material, is illustrated in spring-loaded recessed position within the slot 12 so as to establish an electrical connection between switch contacts 26 and 21. With the code pin 10c oriented 90° to the illustrated position, it is seen that the face slot 12 would be transverse the longitudinal axis of the contact arm member 20 (rather than coextensive therewith) so as to urge the contact arm 20 into the dotted configuration position 20' and complete connection between contact 26 and

contact 22. It is to be understood that the particular contact arm 20 of FIG. 5 might be constructed of a resilient conductive member anchored in a base or mounting means 25 at one end 24 thereof and might be formed with a suitable projection 23 for desired cooperative engagement with the pin slot 12 to effect the connections between contact 26 and one or the other of switch contacts 21 and 22.

Although not particularly illustrated in FIG. 5, it is to be understood that a plurality of contact arms 20 associated with a bank of switches might be employed with each arm being positioned in accordance with the slot orientation on the head of an engaging one of the code pin members 10a-10d. The switch position of each of a plurality of switches addressing the code pin stack of FIG. 4 is thus seen to be determined by the head slot orientation in the associated one of the code pins.

The basic pin row assembly of FIG. 4 may be repeatedly embodied to define paralleled rows of pins as defined by a circular pattern illustrated in FIGS. 6 and 7. By configuring the guide rail members and code pin rows in a circular pattern as depicted in FIG. 6 a basic preset memory drum is defined. FIG. 6 depicts three adjacent rows of pin members 28, 29, and 30 positioned about the periphery of a drum member 27, it being realized that the entire surface of the drum may be configured with code pin rows. Rotation of the drum 27 about its axis 31 by means of a mechanical link 32 with a channel select knob 33, positions selected ones of the plurality of code pin rows into cooperative relationship with a plurality of switch contact arms 20. A typical configuration used for UHF radio control units might contain 15 code pins in each row and a total of 20 stacks or rows carried about the periphery of the drum 27 to permit a channel preset capability. The particular permutation of slot orientation of the code pins in each row effects a predetermined permutation of the associated switches in the bank, and selected permutations may be utilized to establish tuning codes for 20 preset channels.

It is to be realized that, although the depicted embodiment illustrates conductive switch contact arm members being positioned in accordance with the relative orientation of the code pin slots, the switch arms positions might control the actuation of an associated microswitch. Further, one of the pair of switch contacts 21 and 22 illustrated as being associated with each of the contact arms might be embodied in or connected to a single grounding bus bar by means of which predetermined ones of the contact arms 20 may selectively effect a grounding of switch terminal 26 depending upon the orientation of the cooperating code pin head. In general it is seen that the particular orientation of the code pin face slots defines one of two possible electrical switching functions associated with that particular pin and numerous electrical control systems might be embodied with the contact arm or switch position to effect a particular preselected control.

The basic configuration of the present invention is seen to provide a means of selectively actuating a plurality of switches by code pin activating means which requires minimal storage capacity. The "storage" need only comprise a lateral or longitudinal space as concerns the pin row to permit the slight translation necessitated by the diagonal dimension of the pin head as the pin is rotated from one detented position to another and to facilitate the compression spring loading means for the pin row.

Obviously other forms or shapes of material could be used to adapt to the basic memory drum application of the present invention. For example, other retaining means for the code pin assembly might be employed to permit the necessary pin rotation and translation of pins along the axis of the pin row to permit pin face orientation changes while constraining the pins from motion transverse that of the row axis.

The pin assembly of the present invention is seen to possess unique properties of small size with minimal storage space requirements to effect the pin function, extremely low cost, positive displacement control of the cooperating switch contacts, positive detenting for both binary positions, captive pin design, and ease of resetting the code pins when required.

Although the present invention has been described with respect to a particular embodiment thereof, it is not to be so limited as changes might be made therein which fall within the scope of the invention as defined in the appended claims.

5 We claim:

1. A mechanical memory system for effecting a predetermined permutation of switch positions of a plurality of switching means comprising, a plurality of code pin members; each pin member having a substantially square face member, a slot formed in said face member and extending transversely between parallel sides thereof; means for containing said plurality of pin members in a row with coplanar face members, said containing means permitting rotation of each of said pin face members within the plane defined by said pin face members, said containing means permitting translation of said pin members along the axis defined by said row of pins, spring loading means cooperating with at least one of the pins in said row and urging said plurality of pins into a compression loaded parallel-sided orientation; said plurality of switching means arranged in a row with each of said switching means including an actuating arm member in spring loaded relationship with the face member of an associated one of said plurality of pin members, each of said actuating arm members being urged into a first position when a cooperating one of said pin member slots is coextensive with the axis of said switch actuating arm and being urged into a second position when a cooperating one of said pin member slots is transverse the cooperating actuating arm axis, and means responsive to said first and second switch actuating arm positions to effect respective predetermined first and second electrical interconnections.

2. A mechanical memory system as defined in claim 1 wherein said pin row containing means comprises first and second fixed mounting surfaces between which said pin row is confined, said mounting surfaces being space separated by a predetermined distance in excess of the pin row length, said spring loading means comprising a compression spring member carried with the confines of said pin row and acting along the pin row axis to urge said plurality of pin members into said spring-loaded parallel-sided orientation.

3. A mechanical memory system as defined in claim 1 wherein said pin row containing means comprises a pair of parallel spaced guide rail members fixed between first and second mounting plate members, each of said pin members having formed therein a radial groove the diameter of which substantially equals the distance by which said guide rail members are separated, said rail members being received into said pin member radial grooves, whereby said pin members are constrained from translation transverse that of said guide rail axes with limited translation permissible along the pin row axis parallel to that of said guide rail members and with each of said pin members being rotatable within the plane defined by said pin face members.

4. A mechanical memory system as defined in claim 3 wherein each of said square pin member faces is formed with rounded corners of predetermined radius, said pin members being constructed of a lubricous material permitting a selected one of said plurality of pin members to be rotated and effect translation of adjacent ones of said pin members without effecting rotation thereof.

5. A mechanical memory system comprising a plurality of code pin members arranged in a row, each said code pin member being formed with a substantially square face, means for containing said pin members in said row to permit rotation of each pin member within the plane defined by said pin member faces and to permit translation of said pin members along the axis of said pin row while constraining said pin members from translation transverse that of said pin row axis, spring loading means cooperating with at least one of the pin members in said row and urging said plurality of pin members into a compression loaded parallel-sided orientation, each of said pin member faces having a transverse slot extending between parallel sides thereof; a plurality of switching means arranged in a row, each said switching means including an actuating arm member adapted to be urged into spring-loaded

engagement with the face of an individual associated one of said pin members in said row, said actuating arm members having at least a pin face addressing portion thereof with transverse dimension less than that of the width of said pin face slots, whereby those of said actuating arm members addressing a pin face the slot of which is coextensive with the actuating arm member axis are positioned to a first position and those of said actuating members addressing a pin face the slot of which is transverse the actuating arm axis are positioned to a second position, and electrical contact means associated with the actuating arm member of each of said switching means to effect predetermined first and second electrical connections in response to respective first and second positions of the associated actuating arm.

6. A mechanical memory system as defined in claim 5 wherein said pin members are formed of an insulating material, said switching means actuator arm members comprising a conductive material, one end of each said actuating arm member comprising a first output terminal, and further contact means adapted to make a first predetermined electrical connection with the other end of said actuating arm with said actuating arm in the first position thereof, and a second predetermined electrical connection with the other end of said actuating arm with said actuating arm in the second position thereof.

7. A mechanical memory system as defined in claim 5 wherein each of said square pin member faces is formed with rounded corners of predetermined radius, said pin members being constructed of a lubricous material permitting a selected one of said plurality of pin members to be rotated and effect translation of adjacent ones of said pin members without effecting rotation thereof.

8. A mechanical memory system comprising a plurality of parallel rows of code pin members; each of said plurality of rows of code pin members comprising a plurality of code pin members arranged in said row, each said code pin member being formed with a substantially square face, means for containing said pin members in said row to permit rotation of each pin member within the plane defined by said pin member faces and to permit translation of said pin members along the axis of said pin row while constraining said pin members from translation transverse that of said pin row axis, spring loading means cooperating with at least one of the pin members in said row and urging said plurality of pin members into a compression loaded parallel-sided orientation, each of said pin member faces having a transverse slot extending between parallel sides thereof; a plurality of switching means arranged in a row parallel that of said rows of code pin members; each said

switching means including an actuating arm member adapted to be urged into spring loaded engagement with the face of an individual associated one of said pins in a selected one of said rows of code pin members, said actuating arm member having a transverse pin addressing dimension less than that of the width of said pin face slots whereby those of said actuating arm members addressing a pin face the slot of which is coextensive with the actuating arm member axis are positioned to a first position and those of said actuating arm members addressing a pin face the slot of which is transverse the actuating arm axis are positioned to a second position, electrical contact means associated with the actuating arm members of each of said switching means to effect predetermined first and second electrical connections in response to respective first and second positions of the associated one of said actuating arm members, and means for selectively positioning a selected one of said rows of code pin members into cooperative engagement with said plurality of switching means.

9. A mechanical memory system as defined in claim 8 wherein the pin member containing means for each of said rows of pin members comprises a pair of parallel-spaced guide rail members fixed between first and second mounting plate members, each of the pin members in a row of said pin members having formed therein a radial groove the diameter of which substantially equals the space separation of said guide rail member pair, said rail members being received into said pin member radial grooves, whereby said pin members are constrained from translation transverse that of the axes of said guide rail members with limited translation permissible along the pin row axis parallel to that of said guide rail members and with each of said pins in said row being rotatable within the plane defined by said pin face members in said pin row.

10. A mechanical memory system as defined in claim 9 wherein said pairs of parallel-spaced guide rail members comprise adjacent ones of a plurality of guide rail members arranged about the periphery of a drum, and said means for selectively effecting cooperative engagement between a selected one of said rows of pin members and said row of switching means comprises means for rotating said drum to a preselected angular position.

11. A mechanical memory system as defined in claim 8 wherein each of said square pin member faces is formed with rounded corners of predetermined radius, said pin members being constructed of a lubricous material permitting a selected one of said plurality of pin members to be rotated and effect translation of adjacent ones of said pin members without effecting rotation thereof.
